United States Patent Office

Des. 175,781
Patented Oct. 11, 1955

175,781

STEP STOOL

William J. Kranz, Cuba, N. Y., assignor to Viko Furniture Corporation, Eldred, Pa., a corporation of Pennsylvania

Application March 10, 1954, Serial No. 29,453

Term of patent 7 years

(Cl. D15—8)

Fig. 1

Fig. 2

Fig. 1 is a perspective view of a step stool showing my new design, the steps being in retracted position; and Fig. 2 is a perspective view thereof, showing the steps in extended position.

I claim:

The ornamental design for a step stool, substantially as shown.
